UNITED STATES PATENT OFFICE

CLEMENT W. KELL, OF RIDLEY PARK, PENNSYLVANIA, ASSIGNOR TO GENERAL STEEL CASTINGS CORPORATION, OF GRANITE CITY, ILLINOIS, A CORPORATION OF DELAWARE

LOCOMOTIVE STRUCTURE

Application filed March 6, 1931. Serial No. 520,510.

My invention relates to railway rolling stock and consists in a novel main steam cylinder and steam control valve structure for locomotives and may include the combination therewith of parts usually assembled with such structure. My invention is particularly applicable to a structure of this type formed in an integral unit either by use of a one-piece casting or by welding two or more 10 separately formed parts into an integral whole.

My invention contemplates the use of three or more cylinders including the usual steam cylinders at the side of the locomotive and 15 at least one intermediate cylinder. Structures of this type leave little room for clearance between the different members mentioned and the inclusion of all of these parts, together with exhaust steam passages in the 20 desirable one-piece integral form has been attended with difficulties arising from the inability of workmen to get at the walls of the different cylinders and chambers which are spaced from the outer portions of the structure.

The main object of my invention is to overcome these difficulties by arranging the cylinders, control valves and steam passages so 30 that access may be had to the parts hitherto inaccessible without departing from the advantages attending the formation of an integral structure.

In the preferred form of my invention, I 35 form the cylinders and the boiler support integral with the locomotive framing members thereby effecting a maximum of permanent rigidity in the locomotive structure, the attainment of which end is a further object of my present invention.

40 In the accompanying drawings which illustrate my invention—

Figure 1 is a top view of a locomotive cylinder and smoke-box saddle support structure embodying my invention. In this view there is no showing of the lower portions of the structure or of the forwardly and rearwardly extending frame members.

45 Figure 2 is a front elevation of most of the parts shown in Figure 1 but showing the forwardly extending frame members in sec-

tion. This figure is taken substantially on the line 2—2 of Figure 3.

Figure 3 is substantially a horizontal section taken on the line 3—3 of Figure 4.

Figure 4 is a vertical transverse section 55 taken on the line 4—4 of Figure 1.

Figure 5 is a bottom view of the rear portion of the structure shown in Figure 1.

Figures 6 and 7 are vertical longitudinal sections taken on the corresponding section 60 lines of Figure 2.

While my cylinder and boiler support structure may be formed as a separate saddle member and applied to the usual side frames of the locomotive, I prefer to unite the cylinder and associated parts with the frame and indicate the main side members of the framing at 1 and 2, respectively, the same being shown as of box section in front of and in back of the cylinder structure. Main steam 70 cylinders 3 and 4 are located at the sides of frame members 1 and 2 and are integrally united therewith by means of transverse walls 5 and 6, and an intermediate main steam cylinder 7 is located above the frame members, being supported by suitable webs 8 which constitute extensions of the inner walls of the box-shaped members 1 and 2. 75

Each of the main steam cylinders is provided with an individual steam control valve 80 chamber 9, 10 and 11, respectively, the valve chambers being mounted on their respective cylinders by suitable webs 12 which form steam passages between the valves and cylinders. 85

Exhaust steam conduits 13 lead upwardly from each end of steam chamber 10 and then extend inwardly and upwardly and towards each other, merging in a common discharge member 14 located above center cylinder 7, 90 the walls of conduits 13—14 being spaced from the wall of cylinder 7.

Vertical transverse walls 5 and 6 unite with the cylinders and with the walls of conduits 13 to form the upright members of a 95 boiler support which also comprises the horizontal plate 17 provided with inclined flanges 18 at its sides to which the smoke-box sheets may be secured in the usual manner. The upper walls of conduits 13 merge with plate 100

17 and the discharge members 14 preferably extend through and project above the top of plate 17. The structure provides suitable passages A, B, C, D and E whereby access 5 may be had to the portions of the walls of cylinders 4 and 7 and chamber 10 which would be inaccessible if the exhaust steam passageway extended directed inwardly with its lower wall merging with the wall of the center cylinder.

10 Similarly, exhaust steam passages 19 extend upwardly from chamber 9 and then inwardly above and spaced from chamber 11 and curve in a substantially longitudinal direction and also upwardly. They merge 15 with each other at 20 to form a discharge member leading through and projecting above boiler support plate 17 as indicated at 21. The exhaust passages from chamber 11 20 are indicated at 22 and they extend upwardly and inwardly beneath the inner portions of passages 19—20 uniting with each other in a common discharge member 22a, the lower 25 wall of which is spaced from the adjacent portion of the wall of cylinder 7. This arrangement of passages 19 and 22 provides a space H (see Figure 7) between passages 19 and 22 and chamber 11 and cylinder 7 whereby access to the adjacent walls of the passages 29 19 and 22, chamber 11, and cylinder 7 may be had for inspection and repairs.

A substantially horizontal web 23 extends 25 between webs 8 intermediate the upper and lower portions thereof and a cylindrical element 24, having a vertical axis, is mounted on web 23 and forms a pivotal connection for the engine truck (not shown).

The upwardly and inwardly inclined extensions 25 on webs 8 merge with the wall 40 of center cylinder 7 and the adjacent parts form a box-like structure beneath the center cylinder and about the upper portion of element 24. An opening F in wall 5 and an opening G in web 23 provide access to the interior of the box-like structure and to the lower portion of cylinder 7.

While I have illustrated and described a specific form of my invention by which the objects previously referred to are attained, 45 it will be understood that my invention may be embodied in structures different substantially in detail from that described above and I contemplate the exclusive use of those modifications of my invention which come 55 within the scope of my claims.

I claim:

1. In a locomotive structure, a main steam cylinder located at the side of the locomotive structure, a main steam cylinder located adjacent the longitudinal center of the locomotive structure, a steam control chamber located intermediate said cylinders, and an exhaust steam conduit leading from said side cylinder to the portion of said structure 60 above said center cylinder, the wall of said

conduit being spaced throughout its length from the walls of said center cylinder and chamber.

2. A structure as set forth in claim 1 consisting of an integral unit, there being passageways between said conduit and center cylinder and chamber thereby providing access to the opposing walls of the same. 70

3. In a locomotive structure, spaced longitudinal frame members having upwardly and inwardly inclined extensions, a main steam cylinder mounted on said extensions, a transverse web between said members, and an element mounted on said web below said cylinder for pivoting a truck to the structure. 75

4. In a locomotive structure, longitudinal frame members in the form of vertical webs and provided with upwardly extending projections, transverse vertical walls extending between said webs and extending above the same, a substantially horizontal web below the top of said vertical webs and connecting the same, whereby a box-like structure is formed, and a main steam cylinder mounted on the upper portion of said box-like structure. 80

5. In a locomotive structure, longitudinal frame members in the form of vertical webs and provided with upwardly extending projections, transverse vertical walls extending between said webs and extending above the same, a substantially horizontal web below the top of said vertical webs and connecting the same, whereby a box-like structure is formed, a main steam cylinder mounted on the upper portion of said box-like structure, and a truck pivoting element mounted on 95 said horizontal web.

6. In a locomotive structure, longitudinal frame members in the form of vertical webs and provided with upwardly extending projections, transverse vertical walls extending between said webs and extending above the same, a substantially horizontal web below the top of said vertical webs and connecting the same, whereby a box-like structure is formed, and a main steam cylinder mounted on the upper portion of said box-like structure, all of said parts constituting an integral structure, there being openings in certain of the parts to provide access to the lower surface of said cylinder. 105

7. In a locomotive structure, a side cylinder, a steam control chamber above said side cylinder, a center cylinder, an exhaust steam conduit leading from the ends of said chamber towards said center cylinder and curving substantially longitudinally and upwardly above said center cylinder, said conduit being spaced throughout its length from said center cylinder, there being substantial openings between the end portions of said conduit and the space between said conduit and center cylinder being open to the outside of the structure through said openings to permit 110 120 125 130

access to the opposing inside walls of the same for cleaning and inspection purposes.

8. In a locomotive structure, a side cylinder, a steam control chamber above said side cylinder, a center cylinder, a steam control chamber for said center cylinder located between said side cylinder control chamber and said center cylinder, an exhaust steam conduit leading from the ends of said side cylinder control chamber towards said center cylinder and curving longitudinally and upwardly and having a single discharge opening above said center cylinder, said conduit being spaced from said center cylinder and its control chamber to provide access to the opposing walls of the same.

9. In a locomotive structure, a side cylinder, a steam control chamber above said side cylinder, a center cylinder, a steam control chamber for said center cylinder located between said side cylinder control chamber and said center cylinder, an exhaust steam conduit leading from the ends of said side cylinder control chamber towards said center cylinder and curving longitudinally and upwardly and having a single discharge opening above said center cylinder, an exhaust steam conduit leading from said center cylinder control chamber and extending along side of said first mentioned conduit, said conduits being spaced from said center cylinder and center control chamber, the space between said conduits and said center cylinder and control chamber therefor providing access to the opposing walls of the same.

10. In a locomotive cylinder saddle structure, a boiler support plate, elements supporting said plate at the front and rear thereof, a main steam cylinder and a valve chamber therefor located beneath said plate and between said elements, members in the lower part of the structure supporting said cylinder and chamber, a live steam passage leading outwardly in one direction from said chamber, and exhaust conduits leading upwardly from said chamber through said plate, said cylinder and chamber being spaced from all other parts of the structure and said conduits being spaced from said cylinder whereby access to opposing surfaces of said cylinder, chamber, and conduits is facilitated for cleaning and inspection purposes.

In testimony whereof I hereunto affix my signature this 27th day of February, 1931.

55 CLEMENT W. KELL.
